UNITED STATES PATENT OFFICE.

WILLIAM H. MALTMAN AND TIMOTHY R. MCCOY, OF STOCKTON, CALIFORNIA.

COLLAPSIBLE FORM.

1,391,747.

Specification of Letters Patent. Patented Sept. 27, 1921.

Application filed October 18, 1920. Serial No. 417,604.

To all whom it may concern:

Be it known that we, WILLIAM H. MALTMAN and TIMOTHY R. MCCOY, citizens of the United States, residing at Stockton, 5 county of San Joaquin, State of California, have invented certain new and useful Improvements in Collapsible Forms; and we do declare the following to be a full, clear, and exact description of the same, reference 10 being had to the accompanying drawings, and to the characters of reference marked thereon, which form a part of this application.

This invention relates to improvements 15 in devices to be employed in the construction of concrete buildings.

We believe the coming form of construction, especially for large buildings, to be double walls of poured concrete. Single 20 walled buildings of this material have long been used, but are open to the objection that concrete too readily absorbs moisture, and hence the interior of buildings so constructed are damp in wet weather. Hollow 25 blocks have also been used, and solid blocks laid in spaced rows to provide an air passage therebetween. Such a construction is satisfactory to a certain extent, but does not provide a building as rigid as one made of 30 poured concrete, suitably reinforced, and besides is more expensive.

Heretofore, however, as far as we are aware, there has been no way in which to build double poured walls, owing to the almost impossibility of removing the wooden 35 forms commonly used and which would also have to be placed in the air passage or space between the two walls.

The principal object of our invention 40 therefore is to provide a form for this purpose, that is, one which may be placed between the walls to take the place of wooden or other similar forms, and which may be readily collapsed or contracted when the 45 concrete is set, so as to permit of its being instantly withdrawn.

Another object is to provide a form of 50 this character which will form a permanent part of the builder's equipment, since even when once used, its identity is not destroyed as in the case of wooden forms, but can be used over and over again.

A third object is to so construct the form so that each one is a complete unit in itself,

so that it may quickly and easily be put in place and withdrawn and which requires no setting up or putting together when it is desired to utilize the same.

A further object of the invention is to produce a simple and inexpensive device, 60 and yet one which will be exceedingly effective for the purposes which it is designed.

These objects we accomplish by means of such structure and relative arrangement of parts as will fully appear by a perusal of 65 the following specification and claims.

In the drawings similar characters of reference indicate corresponding parts in the several views.

Figure 1 is a perspective elevation of a 70 pair of forms shown in position side by side.

Fig. 2 is a front elevation of a form, the outer plate or cover being removed.

Fig. 3 is a cross section taken on a line 3—3 of Fig. 2.

Fig. 4 is a similar view on a line 4—4 of Fig. 2.

Referring now more particularly to the characters of reference on the drawings, the numeral 1 denotes the form in general, 80 which is a rectangular box-like structure, preferably of sheet metal, and open at the top and bottom. This structure is built up of two spaced and parallel pairs of sidewalls 2 and 3, the pair 2 consisting of an 85 inner plate 4 having an end-flange 5 turned inwardly at right angles, and an outer plate 6 overlapping the plate 4 and having also an end flange 7 parallel to the flange 5, forming an end wall. The plates 4 and 6 90 are held together against relative longitudinal movement while allowing for transverse sliding movement of the one on the other by means of bolts or rivets 8 in the plate 6, which extend through transverse slots 9 in 95 the inner plate 4.

The pair of plates 3 consists of inner and outer plates 10 and 11, mounted for transverse sliding movement by means of slots and rivets 12 and 13, similar to those provided on the plates 4 and 6.

The plates 10 and 11 are also provided with end flanges 14, which are adjacent to but overlapped by the end flanges 5 and 7 of the plates 4 and 6. Bolts or rivets 15 in 105 these outer flanges pass through slots 16 cut in the inner flanges 14, these slots extending in the same plane as the slots 9 and 12.

Thus an inclosed structure is formed which is capable of being varied in size both as to width and thickness.

To mechanically alter the size of the form 5 when desired, we provide the following mechanism, contained within the form.

Fixed to the inner end-flanges 14 and extending lengthwise thereof are bars 17 to which are pivoted adjacent the ends toggle 10 arms 18 connected to a common operating bar 19 extending lengthwise of the form and projecting from the top thereof to a handle 20.

The toggle arms are so angled that when 15 the handle is in its lowermost position, the bars 17 (and hence the form plates 4, 6, etc.) are drawn together or contracted. Also pivoted to the bars 17 intermediate the bars 18 is another pair of toggle arms 21, which 20 are angled oppositely to the bars 18 and are connected to a bar 22 extending alongside the bar 19 and also projecting from the upper end of the form to terminate in a handle 23. In order to expand or contract 25 the width of the form, both bars 19 and 22 must be moved at the same time but in opposite directions. To limit the amount of expanding movement at will, a collar 24 is adjustably mounted on the bar 22, adapted to 30 engage a shoulder 25 on the bar 19, thus permitting opposed movement of the bars and consequent expansion of the form, to the extent determined by the setting of the collar.

35 To alter the thickness of the mold at the same time as the preceding operation is carried out, strips 26 are hinged on the bar 19, and have transverse rollers 27 mounted at their ends, these rollers riding on inclined 40 surfaces 28 on the bars 17, and also bearing against the inner form-plate 4, these inclines slanting outwardly from the bars toward the plate 4 in the direction of movement of the bar 19 to expand the form.

45 Coil springs 29 extend between the two inner form-plates 4 and 10, to draw the same together when the rollers are moved in a direction to contract the form.

At one end of the form flanges 30 extend 50 beyond the end flanges and parallel to the side-plates, these flanges having spaced notches 31 to allow for the passage of the double wall tie-bars 32 therethrough.

In operation, the required number of our 55 improved forms are first expanded to give the desired width then set in position end to end and adjoining as shown in Fig. 1. The tie bars 32 are then placed through the notches 31, after which the outer-wall forms 60 are built up.

The concrete is then poured, and when set, the collapsible forms are withdrawn.

This is done by suitable manipulation of 65 the handles 20 and 23, which contracts the form both ways, freeing it from the concrete

and also withdrawing it from the plane of the tie-bars, so that the form may be readily lifted out from between the walls without frictional contact therewith and without interfering with the tie bars. 70

By means of the two handle-bars which together control the telescoping of the form, and which move in opposite directions, the pressure on one handle in one direction is equalized by the pull on the other, and all 75 pressure and strain is taken off the form itself.

If desired, these forms may be made, to expand or contract only in one direction, by omitting those features which allow its 80 alteration of size in the other direction.

While we have shown handles on the expansion-actuating bars, racks may be provided instead on the adjacent faces of the bars, with a common pinion turned by a 85 crank positioned therebetween.

From the foregoing description it will be readily seen that we have produced such a device as substantially fulfills the objects of the invention as set forth herein. 90

While this specification sets forth in detail the present and preferred construction of the device, still in practice such deviations from such detail may be resorted to as do not form a departure from the spirit 95 of the invention as defined by the appended claims.

Having thus described our invention what we claim as new and useful and desire to secure by Letters Patent is:— 100

1. A collapsible form comprising inclosing walls arranged for telescopic movement to alter the cross sectional area of the inclosure, and means whereby all areas thus obtained will be symmetrical in shape to each 105 other.

2. A collapsible form comprising rectangular inclosing walls adapted for telescopic movement to contract the inclosed area, and horizontally notched and vertically disposed flanges on one of the end walls of the form whereby metal wall-tie bars may be located after the forms are set up in close alinement. 110

3. A collapsible form comprising inclosing walls arranged for telescopic movement to alter the cross-sectional area of the inclosure, a toggle-joint mechanism for altering the width of the form and a roller-and-incline mechanism for altering the thickness thereof, both said mechanisms being enclosed within the form and connected to be actuated simultaneously. 115

4. A collapsible form comprising inclosing walls arranged for telescopic movement 125 to alter the cross-sectional area of the inclosure, means incorporated within the walls for telescoping the same, and means whereby the amount of movement in an expansive direction may be regulated. 130

5. A collapsible form comprising inclosing walls arranged for telescopic movement to alter the cross-sectional area of the inclosure, a toggle-joint mechanism for altering 5 the width of the form and a roller-and-incline mechanism for altering the thickness thereof, both said mechanisms being inclosed within the form, a hand-bar projecting outwardly from one end of the form 10 connected to both mechanisms and adapted

to be moved longitudinally of the form, another hand-bar adjacent the first named bar, and means connecting said last named bar with the toggle mechanism whereby both hand bars must be moved simultaneously but in opposite directions. 15

In testimony whereof we affix our signatures.

WILLIAM H. MALTMAN.
TIMOTHY R. MCCOY.
